US00D582419S

(12) **United States Design Patent**
Sheba et al.

(10) **Patent No.:** **US D582,419 S**
(45) **Date of Patent:** **** Dec. 9, 2008**

(54) **MEDIA DEVICE**

(75) Inventors: **Yaron Sheba**, Mountain View, CA (US);
Moshe Raines, Kfar Saba (IL); **David Koren**, Raanana (IL)

(73) Assignee: **SanDisk Corporation**, Milpitas, CA (US)

(**) Term: **14 Years**

(21) Appl. No.: **29/292,396**

(22) Filed: **Oct. 9, 2007**

(51) **LOC (8) Cl.** **14-02**

(52) **U.S. Cl.** **D14/435**; D14/496

(58) **Field of Classification Search** **D14/435, D14/356, 242, 436, 433, 474, 240, 496, 385, D14/358; 360/97.01, 685, 686, 752, 737, 360/732, 784, 803; 439/135, 144, 139-141, 439/147, 136, 638, 518, 131; 365/51, 63, 365/131; 710/52, 300, 313; 711/115, 103, 711/154, 161-162; 70/58; 323/210; 713/186, 713/1; 382/124; 235/492; D13/147**

See application file for complete search history.

(57) **CLAIM**

The ornamental design for a media device, substantially as shown and described.

DESCRIPTION

FIG. 1 is a perspective view of a media device showing our design;

FIG. 2 is a top plan view thereof;

FIG. 3 is a right side elevation view thereof;

FIG. 4 is a bottom plan view thereof;

FIG. 5 is a left side elevation view thereof;

FIG. 6 is a front elevation view thereof; and,

FIG. 7 is a rear elevation view thereof.

The broken line matter throughout the drawings is not claimed.

1 Claim, 4 Drawing Sheets
